WILLIAM RICHARDSON AND LOUIS BER MÜLLER, OF BALTIMORE,
MARYLAND.

Letters Patent No. 73,837, dated January 28, 1868.

IMPROVED BENDING-MACHINE.

The Schedule referred to in these Letters Patent and making part of the same.

TO ALL WHOM IT MAY CONCERN:

Be it known that we, WILLIAM RICHARDSON and LOUIS BER MÜLLER, of the city and county of Baltimore, and State of Maryland, have invented a new and improved Machine for Bending Tires; and we do hereby declare the following to be a full, clear, and exact description of the same, sufficient to enable those skilled in the art to which the invention appertains to fully understand and use it, reference being had to the accompanying drawings, forming part of this specification, in which—

Figure 1 is a side elevation.

Figure 2 is a top view.

Figure 3 is an end view.

This invention combines a new arrangement of gear, by which great power is exerted at the points which require it, and a new method of adjusting the central roller, by which the tires can be more easily applied and removed than in machines used heretofore.

In the drawings, A A' are corrugated iron rollers, bearing in a fixed iron frame, B, provided with lugs, b b, for the purpose, and supported by a wooden frame, F. To one end of these rollers are fixed two large gears, a a'; of equal size, rotated in the same direction by a small spur-wheel, c, between them. The shaft c', fixed to a short shaft, C', driven by power applied at the crank C'', The whole gearing constitutes an arrangement by which the two rollers are driven with equal velocity, and with immense power. Between the rollers A A' is a vertical sliding frame, D, working in gains or notches in the sides of the iron frame B, and capable of being adjusted, at any required elevation by a screw, S, beneath the frame F. The frame D at its upper extremity bears the middle roller R, a smooth roller working in the same direction as the rollers A A', and exactly half way between them. The tire, in the shape of a straight iron bar, is reduced to the proper shape for fixing upon the wheel, by inserting it between the lower rollers A A' and upper one R, and turning the crank C'' until it has been subjected throughout its whole length to the action of the three rollers.

In order to facilitate the insertion of the iron bar between the rollers, as described, and its removal from them, we make the outer side of the vertical frame D of two parts, one part, d, immovably fixed to the bottom cross-bar, and the other part, d', hinged to the top of the lower piece d, so as to swing outward or inward upon the hinge h. The hinged piece d' carries one of the bearings, r; of the upper or middle roller. The other bearing of the middle roller is in an upright standard, M, on the opposite side of the iron frame B. A link, L, being attached to one of them by a hinge, l, and dropping over a projection, e, upon the other, so as to confine them in the position shown in figure.

When it is necessary to insert the tires between the rollers for bending, we lift the link L off of the projection e, swing the side piece d' outward till the journal of the roller R escapes from its box, raise the end of the middle roller, and insert the bar in its place. The parts are then to be replaced and the tire bent, after which it may be removed in the same manner.

Having thus described our invention, what we claim as new, and desire to secure by Letters Patent, is—
The combination of the roller R with the jointed frame which supports it, constructed substantially as described.
